UNITED STATES PATENT OFFICE.

THOMAS CHARLES GOWER AND JOSHUA HUDSON WILLIAMS, OF GREENVILLE, SOUTH CAROLINA.

AUTOMATICALLY-REVOLVING BILLBOARD.

Application filed October 25, 1926. Serial No. 143,997.

The object of our invention is to provide an improvement in signboards commonly known as billboards whereby such boards may be made in a series of sections joined together, forming a triangle, cube, hexagon, octagon, or other plurality of sections and to provide means for automatically revolving such a sectional billboard and stopping it at desired intervals and capable of arrangement for operating in a variety of ways.

It is also an object of our invention to provide mechanism which can be made of fireproof construction and which is efficient in operation.

We attain these and other objects of our invention by the mechanism illustrated in the accompanying drawings, in which,—

Figure 1 is a perspective view of the exterior of a three-unit machine constructed in accordance with our invention;

Fig. 2 is a detail sectional view on a vertical plane adjacent to and at one side of member 13;

Fig. 3 is a detail sectional view with members 26, 25, 24 and 23 shown in side elevation;

Fig. 4 is a vertical section;

Fig. 5 is a horizontal section on line 5—5 of Fig. 4; and

Fig. 6 is a detail top plan view of members 15, 16, 19, 17 and 20.

Like numerals designate like parts in each of the several views.

Referring to the accompanying drawings we provide a frame 1 of the desired shape, having a floor 2 on which is mounted a bearing block 3 supporting a rotatable center shaft 4, the upper end of which is rotatably mounted in the top supporting frame 8. We provide a revolving sign 5 having any desired number of sides, on the exterior of which posters or signs may be displayed, units of four sides being illustrated in the present drawings. Each of these units has a top supporting frame 7 and base cross beams 6 affixed to the center shaft 4 and to the sides 5. The number of cross beams corresponds with the number of sides to the units, one beam engaging each side. We provide a suitable electric or other motor 11 operatively connected, as by belt 10 to the sign operating shaft 9. Affixed to the under side of the beams 6 and center shaft 4 is a revolving disc 12. We provide starting blocks 26 depending from the under side of

each of the cross beams 6. Keyed on the operating shaft 9 is a starting cam 23 which is provided with a pivotally mounted shock absorbing arm 24 and a spring 25 interposed between said arm and the starting cam 23. Members 24 and 23 operate against block 26 to set the device revolving.

Each wall of the billboard carries a block 18 positioned to be engaged by a brake shoe 17. A retaining or guide arm 20 carried on the outer end of brake rod 16 guides brake shoe 17 in proper alignment with block 18. We provide a suitable brake spring mechanism 19 on each rod 16 as shown in detail on Fig. 2. Brake rod 16 is pivotally connected to a brake releasing cam plate 15 which is mounted on the center shaft 4 as shown in Fig. 2. Cam plate 15 has a flat cam face 21. We provide a sector 13 affixed to operating shaft 9 and of suitable size to frictionally engage the revolving disc 12. We also provide a brake releasing arm 14 carried by sector 13.

In the machine illustrated in Fig. 1 three units are provided, designated respectively, A, B and C. In operation unit A turns ninety degrees and stops. When it has finished turning unit B turns 90 degrees and stops, and then unit C turns ninety degrees and stops. Unit A then starts again and the sequence of movements is repeated.

The rotation of each unit is accomplished as follows. Operating shaft 9, driven by motor 11 turns at the desired speed, say four revolutions a minute. Sector 13 which is rigidly keyed on operating shaft 9 carries the projecting arm 14, which contacts with the cam face 21 of cam 15 and rotates cam sufficiently to pull brake rod 16 inwardly and release brake shoes 17 from frictional contact with blocks 18. As soon as the brakes are released shock absorbing member 24 of starting cam 23 engages the block 26 and starts the sign to revolving. The sector 13 wipes or frictionally engages the under side of disc 12 to maintain revolving movement of the sign for the limited extent required. When the sector 13 has moved through approximately forty degrees the brakes are released from their retracted position and the spring mechanisms 19 again move them into their outermost position into contact with the blocks 18 carried by the walls of the billboard to stop the unit when it has turned ninety degrees.

The cams and sector for unit B are displaced one hundred twenty degrees from those which operate unit A while the corresponding parts for unit C are displaced 5 two hundred forty degrees from unit A. A corresponding arrangement of parts and operating members of suitable number may be provided for billboards when made in the form of a triangle, hexagon, octagon or the like. The units of the billboard are automatically revolved and stopped at pre-determined intervals, singly or in groups, and simultaneously or at alternate periods as may be desired. It is within the contemplation 10 of our invention to suitably ornament the signboards for the purpose of attracting attention. The units when revolved can make one complete sign on the front of the machine, or may be divided into more than one sign. The mechanism is so constructed that 15 wind interference or any other interference in the turning of the units will not do any damage as the units automatically adjust themselves to the proper alignment after 20 such interference.

What we claim is—

1. In an apparatus of the class described, the combination of a revolving billboard having a plurality of sides adapted to carry posters or signs, a stationary frame on which the revolving billboard is mounted, means revolubly supporting the poster-bearing sides, a plurality of brakes adapted to be brought into and out of engagement with the sides of 30 the revolving billboard to intermittently hold same in stationary position, actuating means for setting the device into operation, automatically controlled means for applying and releasing the brakes at pre-determined intervals, a common operating shaft on which 35 the revolving billboard is supported and to which the actuating means controlling the brakes is operatively connected for revolving the billboard and also for controlling the 40 braking means.

2. In an apparatus of the class described, the combination of a revoluble hollow billboard unit having a plurality of sides adapted 45 to carry advertising matter, means for revolubly supporting the unit, power-controlled means for automatically revolving the unit to bring successive signs into view at pre-determined intervals, means for automatically applying brake shoes to bring the 50 unit to a stop in predetermined positions at successive intervals, and a common power-controlled operating shaft arranged to actuate both the unit revolving means and the aforesaid braking means.

3. In an apparatus of the class described, the combination of a billboard unit comprising 55 a hollow structure having a plurality of sides for the display of advertising matter, a central post on which the unit is revolubly mounted, means for mounting said post,

cross beams extending to each of the walls of the unit, a depending lug on each cross beam, a starting cam adapted to be swung into operative engagement with said lug to revolve the unit, a power-controlled operating shaft on which said starting cam is affixed, brake shoes and means for automatically applying said brake shoes to bring the unit to a stop in pre-determined positions at successive intervals, said means being actuated by the aforesaid central post.

4. In an apparatus of the class described, the combination of a billboard unit comprising a hollow structure having a plurality of sides for the display of advertising matter, a central post on which the unit is revolubly mounted, means for mounting said post, cross beams extending to each of the walls of the unit, a depending lug on each cross beam, a starting cam adapted to be swung into operative engagement with said lug to revolve the unit, a power-controlled operating shaft on which said starting cam is affixed, and an automatically controlled braking means arranged for operation at pre-determined intervals to stop the unit after each successive partial revolution.

5. In an apparatus of the class described, the combination of a billboard unit comprising a hollow structure having a plurality of sides for the display of advertising matter, a central post on which the unit is revolubly mounted, means for mounting said post, cross beams extending to each of the walls of the unit, a depending lug on each cross beam, a starting cam adapted to be swung into operative engagement with said lug to revolve the unit, a power-controlled operating shaft on which said starting cam is affixed, and a sector mounted on the operating shaft, a disc mounted on the under side of the cross beams with which the sector frictionally engages to revolve the unit for a pre-determined distance and automatically controlled braking means arranged for operation at pre-determined intervals to stop the unit after each successive partial revolution.

6. In an apparatus of the class described, the combination of a billboard unit comprising a hollow structure having a plurality of sides for the display of advertising matter, a central post on which the unit is revolubly mounted, means for mounting said post, cross beams extending to each of the walls of the unit, a depending lug on each cross beam, a starting cam adapted to be swung into operative engagement with said lug to revolve the unit, a power-controlled operating shaft on which said starting cam is affixed, a sector mounted on the operating shaft, a disc mounted on the under side of the cross beams with which the sector frictionally engages to revolve the unit for a pre-determined distance, a cam disc actu-

ated by the aforesaid sector, a plurality of 5
brake shoes, resiliently controlled rods actuating
said brake shoes, said rods being pivotally
connected to the aforesaid cam disc,
5 whereby the brake shoes are applied with
each successive operation of the sector, to
bring the unit to a stop at successive intervals
as each successive poster side of the
unit is brought into a new display position.
10 7. In an apparatus of the class described,
a series of billboard units each having a
hollow structure having a plurality of sides
for the display of advertising matter, a central
post on which the unit is revolubly
15 mounted, means for mounting said post,
cross beams extending to each of the walls
of the unit, a depending lug on each cross beam,
a starting cam adapted to be swung into
operative engagement with said lug to revolve
20 the unit, a power-controlled operating shaft
on which said starting cam is affixed, a sector
mounted on the operating shaft, a disc
mounted on the under side of the cross
beams with which the sector frictionally
25 engages to revolve the unit for a pre-deter-
mined distance, a cam disc actuated by the
aforesaid sector, a plurality of brake shoes,
resiliently controlled rods actuating said
brake shoes, said rods being pivotally
30 connected to the aforesaid cam disc,
whereby the brake shoes are applied with
each successive operation of the sector, to
bring the unit to a stop at successive intervals
as each successive poster side of the

unit is brought into a new display position, 35
the aforesaid units being actuated from a
common operating shaft.

8. In an apparatus of the class described,
a series of billboard units each having a hollow
structure having a plurality of sides for 40
the display of advertising matter, a central
post on which the unit is revolubly mounted,
means for mounting said post, cross
beams extending to each of the walls of the
unit, a depending lug on each cross beam, a 45
starting cam adapted to be swung into operative
engagement with said lug to revolve
the unit, a power-controlled operating shaft
on which said starting cam is affixed, a sector
mounted on the operating shaft, a disc 50
mounted on the under side of the cross
beams with which the sector frictionally en-
gages to revolve the unit for a pre-deter-
mined distance, a cam disc actuated by the
aforesaid sector, a plurality of brake shoes, 55
resiliently controlled rods actuating said
brake shoes, said rods being pivotally con-
nected to the aforesaid cam disc, whereby
the brake shoes are applied with each suc-
cessive operation of the sector, to bring the 60
unit to a stop at successive intervals as each
successive poster side of the unit is brought
into a new display position, the aforesaid
units being actuated from a common operat-
ing shaft and arranged to be successively 65
revolved.
